SCULLING OAR

Raymond R. Willems and Emmitt N. Willems,
Monticello, Ind.

Application February 1, 1940, Serial No. 316,830

4 Claims. (Cl. 9—24)

This invention relates to a sculling oar adapted for use usually as the sole means of power for a fishing boat, and it is designed to enable the operator or fisherman to impart maximum speed with minimum energy while facing the prow of the boat, one hand being sufficient for operation thereof while the other hand is free for fishing purposes.

It is further aimed to provide a novel structure in which the oar may be attached to the stern of the boat at the stern, will seek a central longitudinal position, and is balanced so as to normally remain in contact with the water and be in a position accessible for grasping and operation.

The more specific objects and advantages will become apparent from a consideration of the description following taken in connection with accompanying drawing illustrating an operative embodiment.

In said drawing:

Figure 1 is a fragmentary elevation of a portion of a boat equipped with our improvements, the boat being partly broken away to disclose details;

Figure 2 is a plan view of the parts in Figure 1;

Figure 3 is an enlarged elevation of the sculling oar, partly broken away to disclose details, and

Figure 4 is a vertical section taken on the plane of line 4—4 of Figure 3.

Referring specifically to the drawing wherein like reference characters designate like or similar parts, 10 designates a conventional row boat or the like such as is used by fishermen. In accordance with the invention, a suitable clamp 11 is rigidly but detachably connected to the stern 12 of such boat, as by means of jaws 13 and screws 14.

Said clamp 11 mounts the sculling oar, generally designated 15. This oar has a central metallic section 16 in the rear end of which a wooden or other handle portion 17 is secured as by a tenon 18 entering a split socket 19 of section 16 with a removable bolt 20 passing through the handle and socket.

Said socket 19 is disposed at an angle to another socket 21 which is located at the other end of section 16 and similarly split, and engaged with the tenon of a sculling oar section 22 which may be of wood or any other material and through which socket 21 and tenon a bolt 23 removably passes. Sculling oar 22 may be of any desired shape and material and it is disposed at an angle to the handle portion 17, and the oar as a whole is balanced in the position shown in Figures 1 and 55

3 by using a weight at the blade as at 24, when desired.

The section 16 has practically universal joint connection to the clamp 11 in that such section has a dependent at 25 pivoted by a pin 26 to a link 27, which in turn is pivoted by a pin 28, disposed at a right angle to the pin 26, and mounted by ears 29 of bracket 34 on the clamp 11. Bracket 34 is swivelly connected to the clamp 11 by a pin or bolt 35, which depends from the bracket and turnably engages an opening 36 in the intermediate, horizontal position of the clamp 11.

It will be realized that but one hand is necessary to operate the sculling oar disclosed, the same being moved in the water from side to side, as suggested in dotted lines in Figure 2. The extent of movement to either side may be limited by a flexible element 30 which is tethered to the handle 17 and has a clasp 31, which may be engaged with a staple or the equivalent 32 fastened to a seat or other part 33 of the boat.

The movement of the oar blade in the water thwartwise while the blade is turned back and forth on its longitudinal axis, similar to the movement of a fish's tail, is a conventional sculling stroke. However, in addition to the oar 15 being swingable in a horizontal plane, by the pin 35 turning in the opening 36, and in a vertical plane, by the oar 15 rocking on its pivot 26, the oar 15 is also mounted to rock on the pivot 28 to cause the oar to be oscillated or turned back and forth substantially on its longitudinal axis to change the pitch of the blade, as is required during the sculling stroke. This movement is accomplished by rocking the handle section 17 on pivot 28 downwardly and toward the direction that the handle section is swinging. This can obviously be accomplished with much less effort than is required to twist the ordinary oar to execute the sculling stroke, as the element 30 is normally taut so that it will pull the handle 17 downwardly as the handle is moved to either side of its central position, and the pressure exerted by the sculler will therefore cause the oar 15 to be rocked, as previously explained, on pivot 28.

It will be noted that when reeling in after releasing the oar, the latter remains in its center position due to the balancing thereof and its pivotal mounting, ready to resume operation. The structure will permit silent operation, is simple to attach to a boat, and may be manufactured in minimum lengths and weights.

Various changes may be resorted to provided

they fall within the spirit and scope of the invention.

We claim as our invention:

1. In combination with the stern of a boat, an oar projecting rearwardly from said stern, means pivotally connecting the oar to the stern on an approximately vertical axis for movement from side to side of the boat, said oar having a downwardly inclined blade end and an approximately horizontal handle end, and a tethered flexible element connected to the handle end at its upper end to provide means to limit the movement of the oar in both directions and to constrain the swinging movement of the oar to an arcuately shaped path the radius of which is equal to the length of the flexible element.

2. A sculling oar construction comprising a mounting means, a metallic oar section having forward and rear portions, said section being pivotally connected approximately at the junction of said portions to the mounting means for movement from side to side of a boat at the stern thereof, said rear portion inclining downwardly with respect to the forward portion, an oar member fastened to said rear portion, a handle fastened to said forward portion, and a tethered flexible element connected to said handle at its upper end to function dually as a means to limit the movement of the oar in both directions and as a means for constraining the swinging movement of the oar, between the limits of its movement, to an arc having a radius equal to the length of the flexible element.

3. A sculling oar construction comprising a mounting means, a metallic oar section having a forward and a rear socket, said section being connected approximately at the junction of said sockets to the mounting means, said mounting means including a universal joint and a swivel connection to mount the oar section for movement from side to side of a boat at the stern thereof, for perpendicular rocking movement, and for a rocking movement substantially on the axis of said oar section, said rear socket inclining downwardly with respect to the forward socket, an oar member fastened to said rear socket and a handle fastened to said forward socket.

4. A sculling oar construction comprising a mounting means, a metallic oar section having forward and rear portions, said section being pivotally connected approximately at the junction of said portions to said mounting means on a plurality of axes including movement from side to side of a boat at the stern thereof, said rear portion inclining downwardly with respect to the forward portion, an oar member fastened to said rear portion, a handle fastened to said forward portion, and a tethered flexible element connected to said handle at its upper end to function as a means for constraining the swinging movement of the oar to an arcuate path the radius of which is equal to the length of the flexible element.

RAYMOND R. WILLEMS,
EMMITT N. WILLEMS.
